UNITED STATES PATENT OFFICE.

RAYMOND GUERLAIN, OF NEW YORK, N. Y.

DESIGN FOR A BOTTLE.

Application filed June 2, 1926. Serial No. 17,919. Term of patent 14 years.

To all whom it may concern:

Be it known that I, RAYMOND GUERLAIN, a citizen of the Republic of France, residing at New York, in the county of New York and State of New York, have invented a new, original, and ornamental Design for Bottles, of which the following is a specification, reference being had to the accompanying drawing, forming a part thereof.

In the drawing:

I claim:

The ornamental design for a bottle, as shown.

RAYMOND GUERLAIN.
